Attorney.

UNITED STATES PATENT OFFICE.

HORATIO G. GILLMOR, OF WASHINGTON, DISTRICT OF COLUMBIA.

ANTICREEPER.

Application filed March 2, 1923. Serial No. 622,378.

To all whom it may concern:

Be it known that I, HORATIO G. GILLMOR, a citizen of the United States, residing at Washington, in the District of Columbia, have invented certain new and useful Improvements in Anticreepers, of which the following is a specification.

My invention relates to devices for preventing the longitudinal creep of railroad rails, such devices being commonly known as anticreepers, rail anchors, creep-checks or rail stays.

The principal object of the invention is to provide a device of this type which will be simple in its construction, inexpensive to manufacture, light in weight, strong and capable of taking a firm and reliable hold on the rail, which will not be affected by vibration, movement of the rail temporarily in a direction the reverse of that in which the rail tends to creep or any other cause tending to loosen the grip of anticreepers on the rails engaged thereby.

A further object is to provide a device constructed in one piece which may be quickly and conveniently applied to the rail with the tools usually employed by track mechanics.

The device possesses other features of novelty and advantage, which, with the foregoing, will be obvious from the following description.

One embodiment of the invention is shown in the accompanying drawings, in which:

Figure 1 is an elevation, with the rail in section, showing the device in position.

Figure 2 is a side elevation, with the cross tie in section, showing the device in position.

Figures 3 and 4 are elevations, with the rail in section, illustrating the method of applying the device to the rail.

Like characters of reference indicate like parts in the several figures of the drawings.

In the embodiment of the invention illustrated in the drawings the rail A rests upon crossties, a portion of one of which is shown and indicated by B, and is of the usual construction with a head C and a base D. The anticreeper E is constructed with a surface F adapted to engage the under portion of the rail head C and a surface G adapted to engage the upper surface of the rail base D at one side of the rail A, and a surface H adapted to engage the edge of the rail base at the other side of the rail A. The portion

I of the anticreeper E, upon which are the surfaces G and F, is adapted to be forced into the fishing space between the head C and base D of the rail A and the portion K of the anticreeper E, upon which is the surface H, is adapted to be positioned outside the base D of the rail A opposite the portion I. The upper free ends of the portions I and K of the anticreeper E which are substantially parallel to each other, are connected the one to the other by curved portions L and M and a straight transverse portion N, either of the faces O or P of which is adapted to engage with the crosstie B. The portion K, the curved portions L and M and the transverse portion N are so formed and related to each other as to permit the anticreeper E to receive the rail base D between the curved portion L and the portion K and allow the end R of the portion K to be brought above the rail base D and also to receive the rail base D between the curved portion M, with the end R of the portion K above the rail base D, and the surface G of the anticreeper E.

The form of anticreeper shown in the drawings is constructed of a rectangular steel bar the ends of which are bent to form the arms or portions I and K. The portions I and K are so formed and related that in the unstressed condition of the anticreeper E, before application to the rail A, the portion K is nearer to the portion I than it is after the anticreeper E has been brought to its final gripping position upon the rail A, consequently the body N is stressed after the anticreeper is in full operative engagement with the rail.

To place the anticreeper E in gripping position upon the rail A it is moved transversely to the rail with the portions I and K inclined until the end R of the portion K will clear the edge of the rail base at one side of the rail with the portion I, in inclined position in the fishing space between the head C and base D of the rail A at the other side. The position of the anticreeper E in relation to the rail A will then be about as illustrated in Figure 3. The anticreeper E is then brought to the position intermediate the positions illustrated in Figures 3 and 4 with the portion K above the base D and the portions I and K vertical. The rail base is now loosely embraced by the anticreeper E, which is then moved, longitudinally upon the rail until

one or the other of the surfaces O or P contacts with a crosstie B. With the anticreeper E thus in contact with the crosstie B, it is moved angularly in a plane transverse to the rail until the surface F begins to engage the under surface of the rail head C, the surface G engages the upper corner only of the rail base D at one side of the rail A and the surface H begins to engage 5 the upper corner of the rail base D at the other side of the rail A as illustrated by Figure 4. To bring the anticreeper from this preliminary position to its operative gripping position on the rail, force must be applied to the anticreeper E. This may be effected by striking the end R of the portion K to drive it downward and by striking the upper part of the portion I, adjacent the surface F to drive it toward 10 the rail head C. Several blows of a hammer or similar implement may be necessary and the force so applied will produce angular movement of the anticreeper E in relation to the rail A with the surface H of 15 the portion K riding on one rail edge, the surface F of the portion I riding on the opposite surface of the rail head C and the surface G pivoting or fulcruming on the corner of the rail base D. Force is applied 20 in the manner described until the angular movement of the anticreeper E brings the surface G into full contact with the upper surface of the rail base D at which time (see Figure 1) the flat portion of the surface F is in full contact with the under surface of the rail head C at one side of the rail A and the surface H of the portion K of the anticreeper E is in full contact with 25 and will press laterally upon the vertical edge of the rail base D at the other side of the rail A. One or more blows upon the portion I of the anticreeper E toward the rail at about mid-height of the fishing space of the rail A will ordinarily be sufficient 30 to firmly wedge the portion I of the anticreeper E in the fishing space between the head C and base D of the rail A.

It will readily be seen that in this final operative position the anticreeper E firmly 35 grips the rail A, the portion I being wedged into the fishing space between the head C and base D of the rail and pressing firmly against it at one side, while the portion K presses firmly against the edge of the rail 40 base D at the other side of the rail; and that it is effectually locked upon the rail A by the position of the portion I of the anticreeper E and the engagement of its surfaces F and G with the head C and base 45 D of the rail A.

The direction in which the rail tends to creep is indicated by the arrow in Figure 2. Contact of the face O with the crosstie B prevents forward movement of the lower 50 portions L, M and N of the anticreeper E

and the grip of the portion I upon the head C and base D of the rail A tends to tilt the anticreeper E and thus to increase the pressure of the surface F upon the under side of the head C and the pressure of the surface G upon the upper surface of the base D of the rail. The gripping action of the anticreeper E upon the rail A will thus be increased by and in proportion to the 55 creeping tendency.

When it is desired to remove the anticreeper E from the rail A this may be done by inserting a wedge between the upper portion of the portion I and driving the wedge longitudinally of the rail to force 60 the surface F outwardly from the rail and out of engagement with the rail head C. The anticreeper E will thus be caused to move angularly in a plane transverse to the rail with the surface H of the portion K riding upward on the rail base edge until the position shown in Figure 4 is reached, after which, with the rail base D loosely 65 embraced by the anticreeper E, it may be inclined from the vertical and move transversely of the rail out of contact therewith.

This invention in its broadest aspect, relating to the type of anticreeper herein disclosed that locks on the rail by engagement with the head and base at one side of the rail and the edge of the base of the rail at its other side is not claimed herein, but will be found claimed in my co-pending application, Serial No. 722,317, filed June 25, 1924.

While I have described one embodiment 100 of my invention, modifications might be made without departing from the principles of the invention. Therefore, I do not wish to be understood as limiting the invention to the particular construction, arrangement and device shown and described except so far as these limitations are specifically set forth in the claims.

I claim:

1. A rail anchor including a straight 110 body member and terminal arms formed on the body member for securing the rail anchor to the rail, said terminal arms being so disposed with relation to the body that their grip upon the head and base of the rail is tightened by movement together in a plane transverse of the rail.

2. A one-piece anticreeper comprising two 115 terminal arms of unequal length, the longer engaging the head and base of the rail at one side and the shorter the base of the rail at the other side, and a straight body held out of contact with the rail when said anticreeper is in operative position on the rail.

3. A one-piece anticreeper formed of a bar 120 of resilient metal bent to form a long arm at one end and a relatively short arm at the other end and provided with a straight intermediate portion, all so formed and related that the long arm may enter the space 125

- between the head and base of the rail at one side and the short arm be brought into gripping engagement with the base at the other side of the rail with the straight intermediate portion out of contact with the rail. 5 of metal bent to form a body portion adapted to engage a crosstie but not the bottom of the rail base, an arm at one end adapted to have surface engagement with the edge of the rail base at one side of the rail, and a portion at the other end adapted to be forced in between the under side of the head and the upper side of the base at the other side of the rail. 60
4. A rail anchor including a transverse body member and terminal arms, the upper portions of which are approximately parallel, formed on the body member and securing the rail anchor to the rail, said terminal arms being so disposed with relation to the body that their grip upon the head and the base of the rail is tightened by movement together in a plane transverse to the rail. 65
- 10 5. An anticreeper comprising a body, and end arms formed integrally with said body and in the same plane therewith and having approximately parallel terminal portions adapted to have direct engagement with the head and base at one side and with the base at the other side of a rail, the arrangement being such that with one arm entered in the space between the head and base at one side the other arm is free to ride on the rail base 70 to a position of surface engagement with the vertical edge thereof, and that when said arm is brought into its full operative engagement with the rail base on its side and said arm first named is forced in between the head and base of the rail on the other side, said body is stressed. 75
- 15 6. In an anticreeper a straight body, adapted to bear against a crosstie, disposed so as to be out of contact with the bottom of the rail base, and approximately parallel end portions disposed so as to rigidly engage the under side of the head and upper side of the base at one side of the rail and to have surface engagement with the edge of the rail base at the other side of the rail, when said body is forcibly moved angularly transversely of the rail, and thereby lock said anticreeper in position on the rail. 80
- 20 7. A rail anchor comprising a straight body member adapted to engage a crosstie below and to be held out of contact with the bottom of the rail base, and approximately parallel end portions formed on the body member for securing said anticreeper to the rail, said body member being adapted to be forcibly moved on the rail after being placed thereon whereby one end portion is wedged in between the under side of the head and the upper side of the base at one side of the rail and a vertical surface of the other end portion firmly pressed against the edge of the rail base at the other side of the rail. 85
- 25 8. An anticreeper formed of a single bar of metal bent to form a body portion adapted to be forced in between the under surface of the head and the upper surface of the base at one side of the rail and the other end bent to form an arm adapted to have rigid surface engagement with the vertical edge of the rail base at the other side of the rail, said arm being so disposed with relation to the other portion that said anticreeper may first be placed upon the rail with the intermediate portion of said bar in contact with a crosstie below and with said arm and other end portion above the base of the rail, and then forced into position by driving said arm downwardly and said other end portion in between the head and base of the rail. 90
- 30 9. An anticreeper comprising a bar having one end bent to form a portion adapted to be forced in between the under surface of the head and the upper surface of the base at one side of the rail and the other end bent to form an arm adapted to have rigid surface engagement with the vertical edge of the rail base at the other side of the rail, said arm being so disposed with relation to the other portion that said anticreeper may first be placed upon the rail with the intermediate portion of said bar in contact with a crosstie below and with said arm and other end portion above the base of the rail, and then forced into position by driving said arm downwardly and said other end portion in between the head and base of the rail. 95
- 35 10. The combination with a crosstie and a railroad rail having a head and a base flange, of an anticreeper provided with a part engaged with the bottom of the head and top of the base flange, a part engaged with the crosstie to prevent forward movement, and a part approximately parallel to said part first named having surface engagement with the vertical edge of the base flange to prevent lateral displacement. 100
- 40 11. A rail anchor comprising a straight transverse bar adapted to engage a crosstie but not the rail bottom and provided with a terminal arm at one end adapted to have surface engagement with the rail base edge, and with an arm at the other end thereof approximately parallel to said arm first named adapted to be driven transversely of the rail toward and under the rail head to effect a gripping action and lock said anchor in position. 105
- 45 12. A rail anchor comprising a bar bent to form a body portion adapted to engage a crosstie below but out of contact with the bottom of the rail base, an end portion adapted to be driven in between the bottom of the head and the top of the base at one side of the rail, and an end portion having a surface adapted to engage the vertical edge of the rail base at the other side of the rail. 110

H. G. GILLMOR.
